UNITED STATES PATENT OFFICE

117,702

DESIGN FOR A HEARSE BODY

Earl L. Schofield, Freeport, Ill., assignor to Henney Motor Company, Freeport, Ill., a corporation of Delaware

Application December 12, 1938, Serial No. 81,730

Term of patent 7 years

To all whom it may concern:

Be it known that I, Earl L. Schofield, a citizen of the United States, residing at Freeport, in the county of Stephenson and State of Illinois, have invented a new, original, and ornamental Design for a Hearse Body, of which the following is a specification, reference being had to the accompanying drawing, forming part thereof.

In the drawing:

Fig. 1 is a side view of a hearse body embodying my design, the opposite side of the body being the counterpart of that appearing in this view, and

Fig. 2 is an enlarged diagrammatic outline of a section taken on the line 2—2 of Fig. 1.

The general configuration of the hearse body of my design is understood to be conventional.

The dominant features of the design reside in the portions shown in full lines in Fig. 1.

I claim:

The ornamental design for a hearse body, substantially as shown and described.

EARL L. SCHOFIELD.
